U. DITTMAR

DRAWING ROLLER FOR SPINNING MACHINES

Filed June 18, 1925

Inventor
Udo Dittmar
by his attorney
C. W. Burbank

UNITED STATES PATENT OFFICE.

UDO DITTMAR, OF FREIBURG IM BREISGAU, GERMANY.

DRAWING ROLLER FOR SPINNING MACHINES.

Application filed June 18, 1925, Serial No. 37,963, and in Germany June 21, 1924.

My invention relates to improvements in drawing rollers for spinning machines, in which the sliver from a carding machine is elongated before being passed to the spinning apparatus. The object of the improvements is to provide means whereby the sliver is supported while passing between the successive pairs of drawing rollers. Another object of the improvements is to provide subsidiary drawing rollers intermediate the main drawing rollers for stretching the sliver, the said subsidiary drawing rollers being connected so as to stretch short fibres of the sliver and to permit the passage in long fibres therethrough without drawing the same. With these and other objects in view my invention consists in providing subsidiary pairs of drawing rollers intermediate the main rollers, the working faces of the said subsidiary rollers being slightly spaced from each other so as to permit long fibres to pass between the same without being drawn, and to stretch only short fibre material.

For the purpose of explaining the invention an example embodying the same has been shown in the accompanying drawings, in which the same reference characters have been used in all the views to indicate corresponding parts. In said drawings,

Fig. 1, is a diagrammatical elevation of the apparatus,

Fig. 2, is a top-plan view with the top rollers removed,

Fig. 3, is a detail view showing one of the subsidiary rollers, and

Fig. 4, is a similar view showing a modification.

In the example shown in the figures the apparatus comprises back bottom drawing rollers a^1 , middle bottom drawing rollers b^1 and front bottom drawing rollers c^1 , and back top rollers a^2 , middle top rollers b^2 and front top rollers c^2 , the bottom rollers being mounted in roller stands p , and the top rollers in cap bars n , as is known in the art. Between the pairs of rollers c^1 , c^2 and b^1 , b^2 there is a pair of subsidiary rollers d^1 , d^2 . In the example shown in the figures the bottom roller d^1 is driven from the bottom roller b^1 by suitable means such as a band or a belt f^1 , and it carries along the subsidiary top roller d^2 by friction. Between the pairs of rollers a^1 , a^2 and b^1 , b^2 a subsidiary pair of rollers g^1 , g^2 is provided, the roller g^1 being driven by suitable means, as for instance, a belt f^2 from the roller a^1 , but

I wish it to be understood that my invention is not limited to the manner of driving the said rollers d^1 and g^1 . On the stand p a stand h is mounted which is fixed in position relatively to the stand p by means of a screw i , lateral displacement of the said stand h being prevented by lugs k depending from the said stand h . The stand h provides a bearing for the subsidiary bottom rollers g^1 and d^1 . The subsidiary top rollers d^2 and g^2 are mounted on the cap bar n .

In Fig. 3 I have shown a roller which can be used either as a subsidiary bottom roller g^1 or d^1 or a subsidiary top roller d^2 or g^2 . As shown the said roller is slightly reduced in diameter at its median or working part r^1 as compared to its ends r^2 , the difference of the diameters being not more than a fraction of a millimeter. In Fig. 4 I have shown a modification in which the working face r^3 of the cylinder is provided with circumferential grooves. Preferably the roller is mounted so that the projecting portions between the grooves are slightly spaced from the cooperating roller. By thus providing a slight clearance between the working faces of the rollers the sliver is held under light pressure permitting the long fibres to slide between the rollers without being torn.

In Fig. 2 I have shown an example in which a plurality of loose bottom rollers are connected with one another, so that a continuous series extending the whole length 90 of the machine is produced. For each side of such loose or connected bottom rollers a common support may be provided on the stand.

I claim:

1. In an apparatus of the class described, the combination, with two pairs of main drawing rollers, of a pair of subsidiary drawing rollers having smooth working faces slightly spaced from each other.

2. In an apparatus of the class described, the combination, with two pairs of main drawing rollers, of a pair of subsidiary drawing rollers having smooth working faces, the working face of one of said rollers being reduced in diameter as compared to other portions of the roller.

3. A drawing apparatus for spinning machines, including a plurality of pairs of main drawing rollers, and an auxiliary pair of rollers within the stretching zone between two adjacent pairs of said main drawing

rollers, one of said auxiliary rollers having its end portions contacting with the other auxiliary roller whereby one is frictionally driven from the other and having its intermediate portion smooth and of slightly smaller diameter.

4. A drawing apparatus for spinning machines, including two pairs of main drawing rollers, and an auxiliary pair of rollers therebetween, said auxiliary rollers having their end portions in frictional driving engagement and their intermediate portions smooth and slightly spaced apart.

5. A drawing apparatus for spinning machines, including a plurality of drawing rollers arranged to form a stretching zone, certain of said rollers being arranged in pairs to grip and stretch the sliver passing therebetween, and certain of said rollers being arranged in pairs to permit slippage of the sliver.

6. A drawing apparatus for spinning machines, including a plurality of drawing rollers, certain of said rollers being arranged in pairs to grip and stretch the sliver, and one or more of said rollers having a smooth surface slightly lower than the bearing surface thereof to permit slippage of the longer fibers of the sliver.

7. A drawing apparatus for spinning machines, including a plurality of drawing rollers, two of said rollers having their surfaces acting to grip the sliver passing therebetween, and two of said rollers having their working surfaces slightly spaced, and means for driving one of said second mentioned rollers from one of said first mentioned rollers.

8. A drawing apparatus for spinning machines, including a plurality of drawing rollers, two of said rollers having their surfaces acting to grip the sliver passing therebetween, and two of said rollers having their working surfaces slightly spaced, and a belt for driving one of said second mentioned

rollers from one of said first mentioned rollers.

9. A drawing apparatus for spinning machines, including two pairs of drawing rollers having their surfaces coating to form a stretching zone between said pairs, and an intermediate pair of stretching rollers, one of said intermediate rollers having its working surface slightly spaced from the other, and a belt for driving one of said intermediate rollers from one of said first mentioned rollers.

10. A drawing apparatus for spinning machines, including a stand, a plurality of lower main stretching rollers mounted thereon, an auxiliary member serving to retain said rollers in position, lower auxiliary rollers mounted in said member, a pivoted cap bar having upper main rollers for cooperating with said lower main rollers and also having upper auxiliary rollers for cooperating with said lower auxiliary rollers, and means for driving said lower auxiliary rollers from said lower main rollers.

11. A drawing apparatus for spinning machines, including a stand, a plurality of lower main stretching rollers mounted thereon, an auxiliary member serving to retain said rollers in position, lower auxiliary rollers mounted in said member, a pivoted cap bar having upper main rollers for cooperating with said lower main rollers and also having upper auxiliary rollers for cooperating with said lower auxiliary rollers, and means for driving said lower auxiliary rollers from said lower main rollers, each of said upper rollers being frictionally driven from its corresponding lower roller, and one of each pair of auxiliary rollers having its working surface slightly spaced from the working surface of the cooperating auxiliary roller.

In testimony whereof I have affixed my signature.

UDO DITTMAR.
